UNITED STATES PATENT OFFICE.

GEORGE S. CLARK, OF BOWLING GREEN, KENTUCKY, ASSIGNOR, BY MESNE ASSIGNMENTS, TO CLARK PATENT TUBING CO., OF WHEELING, WEST VIRGINIA, A CORPORATION OF WEST VIRGINIA.

BLASTING SHELL.

Application filed March 15, 1921, Serial No. 452,405. Renewed January 9, 1923.

To all whom it may concern:

Be it known that I, GEORGE S. CLARK, a citizen of the United States, residing at Bowling Green, in the county of Warren and 5 State of Kentucky, have invented certain new and useful Improvements in Blasting Shells; and I do hereby declare the following to be a full, clear, and exact description of the invention, such as will enable others 10 skilled in the art to which it appertains to make and use the same.

In mining operations the best results are attainable by the use of a shell of proper size both as to diameter and length.

15 The present invention provides a shell in flattened form for convenience of storing and handling and embodying a plurality of sizes formed by longitudinal folds or crimps which normally are confined by a sealing 20 strip, one or more of the folds or crimps being releasable by severance of the sealing strip, whereby to provide a shell of required size, said sealing strip also serving to connect the longitudinal edge portions of the 25 shell forming strip.

The invention also aims to provide a shell 30 of the character aforesaid which admits of the required length being readily obtained without measuring or having recourse to scale 35 graduations. This object is attained by folding the tube backward and forward upon itself in uniform lengths, the folds being of predetermined extent, i. e. form, size or any given number of inches, and utilized as a unit of measure in determining the required length.

The invention furthermore provides a shell capable of variation in diameter either 40 by folding or crimping longitudinal portions, in which case the tube will be of maximum diameter and reducible by folding or crimping longitudinal portions thereof, or by releasing longitudinal folds or crimps. In the latter case the tube will be of minimum 45 diameter and embody confined folds or crimps which are released to provide the shell of required diameter.

The invention also aims to provide a tube 50 embodying sealing means which may be in the form of a continuous linear strip, or a plurality of transverse strips. The linear strip in one form includes marginal tabs for confining the reducing folds and the trans-

verse strips in one embodiment have end portions free to serve as fold securing means. 55

Other objects and advantages will be apparent and suggest themselves as the nature of the invention is understood.

While the drawings illustrate an embodiment of the invention it is to be understood 60 that in adapting the same to meet different conditions and requirements, various changes in the form, proportion and minor details of construction may be resorted to without departing from the nature of the invention. 65

Referring to the accompanying drawings forming a part of the specification,

Figure 1 is a perspective view of the blasting tube in packet form, 70

Figure 2 is a detail perspective view of a portion of the tube having a longitudinal edge portion folded and secured,

Figure 3 is a perspective view of a modification in which the linear sealing strip is 75 provided along opposite longitudinal edges with marginal tabs,

Figure 4 is a perspective view of the form of tube shown in Figure 3, having opposite edge portions folded and made secure, 80

Figure 5 is a further modification showing transverse sealing strips,

Figure 6 is a further modification showing opposite ends of the transverse strips loose and adapted to secure opposite folded edge 85 portions of the tube,

Figure 7 is a perspective view of a different form of tube reduced to packet form and embodying longitudinal crimps,

Figure 8 is a transverse section of the 90 form of tube illustrated in Figure 7,

Figure 9 is a further modification showing a strand for severing the sealing strip,

Figure 10 is a transverse section of the 95 form of tube shown in Figure 9,

Figure 11 is a view similar to Figure 10 with the size fold released and extended.

Figure 12 is a perspective view of a further modification in packet form,

Figure 13 is a transverse section of the 100 form of tube shown in Figure 12 having one of the size folds released and extended,

Figure 14 is a view similar to Figure 13 having all the size folds released and extended, 105

Figure 15 is a further modification show-

ing the linear sealing strip extending the full width of the flattened tube, and

Figure 16 is a further modification showing the longitudinal edge portion of the tube forming strip and a side fold secured by means of transverse sealing strips.

Corresponding and like parts are referred to in the following description and designated in the several views of the drawings 10 by like reference characters.

The shell is preferably provided in flattened form to economize space and for convenience of handling. The shell is formed from a strip 1 of paper or other suitable sheet material said strip being of any desired length and width. In the formation of the shell or tube, the longitudinal edge portions of the strip 1 are brought together and preferably overlapped and secured in any preferred way. Portions of the tube or shell thus formed may be longitudinally folded or crimped, the folds being designated at 2 and the crimps at 3. The number of longitudinal folds 2 or crimps 3 will depend upon the range of adjustment of the tube or shell to meet predetermined requirements. The folds or crimps may occupy any relative position in the width of the tube, as will be readily understood.

Longitudinal edge portions of the tube or shell forming strip 1 and the several size forming folds 2 and crimps 3 are made secure and confined by means of a sealing strip, the latter being applied in such manner as to overlap the joints and made secure by a suitable adhesive. The tube or shell in its initial form is of a determinate size which may be maximum or minimum. If of minimum size and a larger sized tube or shell is required, one of the folds 2 or crimps 3 is released and opened out with the result that the diameter of the resultant tube or shell is increased by the amount contained in the size fold or crimp released. If a tube or shell of still larger diameter is required, another size fold or crimp is released and extended, and so on for each size fold or crimp within the range of adjustment of the tube or shell. For convenience of severance of the sealing strip 4 along a fold line, a strand 5 may be provided and disposed beneath the sealing strip adjacent the fold line of the size fold to be released. Another way of facilitating the severance of the sealing strip is the provision of a weakened line 6 which may be formed by closely related perforations in a manner well understood in the paper manufacture art. The size folds or crimps may be released in any desired or preferred way by severance of the sealing strip 4 along the fold lines. It will be understood that the strip 4 serves both to seal the tube or shell and to confine the several size folds or crimps.

65 In the form of tube including confined

size folds or crimps, the sealing means may consist of a continuous linear strip 4 or a plurality of transverse strips 4^a. When the tube is of the form requiring release of the size folds or crimps to increase the diameter of the tube, the confining or sealing strips may be severed in any manner to effect the release of the size fold or crimp.

When the tube, in its initial form, is of maximum diameter, that is, adapted for the largest sized shell, the diameter is reduced when a shell of smaller size is required by folding or crimping portions of the tube, the folded or crimped portions being secured by use of a continuous linear strip 4 or a plurality of transverse strips 4^a. The continuous linear strip 4 is provided along one or both longitudinal edges with marginal tabs 7 which normally are free and supplied with an adhesive, the latter being moistened preliminary to pressing the tabs 7 upon the folds or crimps for securedness thereof. When the transverse strips 4^a are employed, one or both end portions of such strips are loose, whereby they may be utilized in the capacity of the tabs 7 and in a like manner for securing the folds or crimps when the diameter of the tube is reduced by folding or crimping longitudinal portions thereof. To facilitate the folding or crimping of the tube, the same is provided with one or more lines of perforations 8 which serve both as guide means as well as facilitating the folding or crimping of the tube.

In the preferred marketable form, a given length of tube is reduced to the form of a packet by reversely folding the same, as indicated at 9, the folds being of uniform and predetermined length whereby a shell of required length may be quickly obtained by extending one or more of the folds 9 as may be required. The linear folds 9 enable the length of the tube to be reduced to convenient form and also serve as guide means when separating a portion of the tube to provide a shell of required length. The linear folds 9 may be six, eight or ten inches in length more or less as may be determined upon. If the folds 9 are eight inches in length and it be required to form a shell eight inches long, a portion of the tube is severed from the packet corresponding to the length of one of the folds. However, should the shell required be sixteen inches in length, a portion of the tube is removed corresponding to the combined length of two of the folds. The length of the folds being known, a shell of required length may be readily formed by separating a portion of the tube from the packet, the length being approximately determined by reference to the folds and sectional parts thereof, as will be readily understood.

The tube in packet form is compact and may be readily handled and supplies the

miner with an article whereby a shell of required length and diameter may be readily formed and when completed, may be handled without spreading or buckling which are serious objections to the successful use of the ordinary shell.

What is claimed is:

1. As a new article of manufacture, a multiple blasting shell or tube comprising a plurality of independently confined size folds or crimps whereby to provide a shell of required diameter by releasing and extending one or more of the size folds or crimps.
- 15 2. A multiple blasting shell or tube embodying a plurality of size folds or crimps, and independent means normally confining each of said folds and overlapping and separable in line with the joints thereof, whereby to provide a shell of given diameter, said shell being adapted for diametric enlargement by releasing one or more of said size folds.
- 20 3. A multiple blasting shell or tube embodying a plurality of size folds or crimps, and a sealing strip for confining the size folds or crimps and adapted for severance to release the size folds or crimps to admit of enlarging the shell or tube to meet existing requirements.
- 25 4. A multiple blasting shell or tube consisting of a strip having its longitudinal

edges brought together and an intermediate portion folded, and a sealing strip for securing the size fold and the longitudinal edges of the shell forming strip.

5. A multiple shell or tube for blasting purposes consisting of a strip having its longitudinal edges brought together and overlapped, and having portions upon opposite sides of the joint thus formed folded to provide size folds, and a sealing strip for securing the size folds and the edges of the shell forming strip.

10 6. A blasting tube consisting of a strip having its longitudinal edges brought together, a sealing strip securing the brought together edges and having loose portions for confining portions of the tube when folded to reduce the diameter thereof.

15 7. A blasting tube having longitudinal weakened lines to designate folds for reducing the diameter of the tube, and having its longitudinal edges brought together, and a sealing strip securing the brought together edges of the tube forming strip and having loose portions for confining the reducing folds.

In testimony whereof I affix my signature in presence of a witness.

GEORGE S. CLARK.

Witness:

BENNETT S. JONES.
